MOUNTING MEANS FOR DEMOUNTABLE
CONTAINERS

Jack E. Gutridge, Dyer, Ind., assignor to Pullman Incorporated, Chicago, Ill., a corporation of Delaware
Filed June 5, 1964, Ser. No. 372,926
6 Claims. (Cl. 105—366)

The present invention relates to railway flat cars for hauling demountable containers and more particularly to the mounting brackets for locating and locking the containers on the railway flat cars.

Demountable containers of the type which are used for universal carrier interchange such as between railway cars, ships, semi-trailers and aircraft are currently constructed of standard length, width and height dimensions so as to permit the universal interchange thereof. These containers are further provided with indexing and attachment structures which are rendered complementary to indexing and locating means employed on the particular freight vehicle on which the container is to be carried.

These complementary indexing and locating means on the container may be of basically different designs employing only such structure that is necessary to adapt it for use with the standardized container attachment structure to perform the function required thereof.

Hauling of the demountable containers by way of rail transportation may be performed on railway cars of the flat car type and having container mounting arrangements provided on the car for locating and locking the container thereon. The flat cars may also be suitable for use in the piggyback operation of transporting semi-trailers, auto racks and the like. When the flat car is used for all the aforementioned purposes, it is essential that the floor structure be made substantially free of any upstanding obstruction. In the event that the flat car is used for hauling trailers an obstruction in the path of movement of the wheels tends to slow down the loading and unloading operation of the semi-trailers. It is obvious, of course, that an obstruction on the floor would interfere with the attachment and positioning of an auto rack thereon.

Heretofore in order to avoid the obstruction of the floor of the car, the container mounting arrangements or means have generally been designed for location on or adjacent to the side sill. The mounting means have been generally constructed for pivotal movement inboard and outboard of the side between an operative position on the car floor and a stored position on or beneath the side sill. These prior attachment means have been extremely cumbersome and also required additional structure to fasten them in the stored position. Accordingly not only were the attachment means bulky and cumbersome but also expensive to manufacture.

It is an object of the present invention to provide a new and improved container mounting structure for railway cars which overcomes the difficulties encountered heretofore.

It is a further object to provide a container mounting structure which is of simple design and economical to manufacture.

It is still a further object to provide a container mounting structure which is foldable between an inoperative position flat on the deck of the car to an erect operative position in which position the container mounting structure incorporates a means for indexing and locating the container lengthwise on the flat car.

It is another object to provide a container mounting structure which is constructed so as to be foldable to a stored position substantially flush with the floor of

2

the railway flat car to an erect operative position in which the members forming the structure are constructed to provide mutual support for each other, thereby to impart rigidity to the container mounting structure.

5 It is still another object to provide a container mounting structure including a pair of foldable members which include means which adapt to coat with the corners of the container so that in the operative erect position of the foldable members, the container is located both longitudinally and laterally of the car.

10 It is another object of the invention to provide trailer mounting means including a pair of plate members including index means provided on each of the plate members in which the plate members are foldable from an inoperative stored position adjacent the floor of the car to an erect operative position and wherein the index means on the respective plate members coat so as to cooperate with complementary locating means provided in the container.

15 It is yet another object of the invention to provide a container mounting means including a pair of plate members which are foldable relatively to each other from an inoperative position flush with the floor of the car to an operative erect position wherein the plate members include means insertable into an indexing opening provided 20 in the bottom of the car and wherein said plate members include means for retaining the container latched to the mounting means.

25 Further objects and features will hereinafter appear.

In the drawings:

30 FIG. 1 is a perspective view of a railway flat car having the container mounting arrangement of the present invention incorporated thereon;

35 FIG. 2 is a cross-sectional view taken generally along the lines 2—2 of FIG. 1 and showing in particular the manner in which the containers are carried on the car on the container mounting arrangement of the present invention.

40 FIG. 3 is a view similar to FIG. 2 but showing the trailer mounting arrangement in the stored inoperative position and with the wheels of a tractor or semi-trailer passing thereover;

45 FIG. 4 is a perspective view of the other corner of the container mounting arrangement showing the components thereof in the operative position and supporting a container as shown in phantom;

50 FIG. 5 is a perspective view similar to FIG. 4 but showing the components of the container mounting arrangement in the collapsed stored position on floor of the car;

55 FIG. 6 is a transverse elevational view of the container mounting arrangement taken generally along the lines 6—6 of FIG. 4;

FIG. 7 is a longitudinal elevational view of the container mounting arrangement taken generally along the lines 7—7 of FIG. 4;

FIG. 8 is a perspective view of the container mounting arrangement of FIG. 5 showing the latter in the stored position and an arrangement for recessing the components 60 within the floor of the car;

FIG. 9 is a side elevational view of the recess arrangement shown in FIG. 8;

FIG. 10 is a perspective view of another form of container mounting arrangement which is adapted to be 65 used for concurrently mounting the ends of two adjacent containers thereon and showing the components of the container mounting arrangement in the erect operative position thereof;

70 FIG. 11 is a perspective view similar to FIG. 10 but showing the components thereof in the stored position adjacent the floor of the railway car;

FIG. 12 is a transverse elevational view of the container mounting arrangement shown in FIGS. 10 and 11 taken generally along the lines of 12—12, FIG. 10;

FIG. 13 is a longitudinal elevational view of the mounting structure shown in FIGS. 10 and 11 but taken generally along the lines 13—13 of FIG. 10;

FIG. 14 is a perspective view of another embodiment of a container mounting arrangement wherein there is utilized an indexing means cooperative with a standard opening in the base of the container; the components of the container mounting arrangement being shown in their inoperative stored position adjacent the floor of the car;

FIG. 15 is similar to FIG. 14 but taken along the opposite side of the car and showing the components of the container mounting arrangement in the erect operative container supporting position.

FIG. 16 is a lateral elevational view of the container mounting arrangement shown in FIG. 14 and FIG. 15 taken generally along the line 16—16 of FIG. 15; J-1(9) Ray Harmon 40180 Job Comp. June 4-66

FIG. 17 is a longitudinal elevational view of the container mounting arrangement of FIG. 14 and FIG. 15 taken generally along the lines 17—17 of FIG. 15;

FIG. 18 is a perspective view of another embodiment of container mounting arrangement adapted to utilize the opening in the underside of the container and wherein two containers are disposed in close end to end relationship so that the container mounting arrangement concurrently supports the adjacent ends of the container;

FIG. 19 is similar to FIG. 18 but taken along the opposite side of the car and showing the components of the container mounting arrangement in the erect operative container supporting position.

Referring now to the FIGS., particularly FIGS. 1 and 2, there is shown a flat open deck portion of a railway car 10 suitable for piggyback operation and having embodied thereon the new and improved container mounting arrangement of the present invention. The railway flat car 10 comprises generally an underframe 11 including a center sill 12 from which there project the usual bolsters 13 and crossbearers 14. Fixed to the ends of the bolsters 13 and crossbearers 14 along each side of the car are side sills 15. Fixed between the side sills 15 and the center sill 12 are the usual floor sheets 16, fixed at their inner end to the top plate 17 of the center sill 13. The underframe 11 is suitably mounted on wheels or trucks 18.

Extending lengthwise of the floor 16 are a pair of transversely spaced channels 19—19 which are arranged to carry the vertical weight of the containers C supported on the floor 16. The containers C are adapted to be carried on the floor 16 and may be of standardized dimensions in respect to the length, width and height thereof. These standards may conform to those accepted by the American Standards Association to permit a full interchange of the containers among the various forms of transportation such as rail, ship, aircraft, truck and the like. The containers may be provided also with various standard types of fittings and openings for accommodating locking and indexing means provided on the different types of transportation by which the container is to be transported. The fittings and openings are standardized in size and location to facilitate the design of equipment employed on the transportation media.

As shown, the containers C on the railway vehicle 10 in FIGS. 1, 2 and 3 are supported on the channels 19—19 and there is fastened to the floor 16 a plurality of container support brackets 20 and 21. The support brackets 20 are adapted to locate the larger size containers on the railway car while the support brackets 21 are adapted to hold the adjacent ends of two of the smaller containers in position on the railway car 10 as more fully to be explained hereinafter.

As shown, the container or support brackets 20 and 21 are each constructed to be collapsible to a position substantially flush with the floor 16. This permits the tractor

and semi-trailers which are also adapted for use on the flat car to be easily and rapidly transported over the floor and thereby facilitate the unloading and loading of the semi-trailer from the railway car 10. As shown, in particular in FIG. 3, the container brackets in the foldable position project only slightly above the level of the floor 16 and are located so as to generally underlie the outer of the dual wheels of the tractor and semi-trailer. This permits the semi-trailer and tractor to be rapidly driven over the top of the floor 16 because the flat bracket structure is not such an obstruction which would cause the semi-trailer or tractor to bounce or jostle out of control when being driven across the floor 16 at a moderate rate of speed.

As shown, in particular in FIGS. 4 through 7, the corner container support brackets 20 are each of substantially identical structure such that only one of the brackets 20 need be described. The bracket 20 comprises essentially a foldable member 22 extending transversely of the car and a folding member 23 extending lengthwise of the car parallel with the side sill 15. The longitudinal foldable member 23 is turnable or pivotally mounted about pivot pins 25 mounted on trunnions 24 which may be fixed to the floor 16 as by welding or the like.

25 The transverse foldable member 22 is mounted for pivotal movement transversely to the car between the folded position shown in FIG. 5 to the erect position shown in FIG. 4 by means of pivot pin 26 supported on a base trunnion 27, fixed on the deck 17 inwardly on the side sill and a trunnion bracket 28 which may be fixed to the vertical web of the side sill 15. As shown, the longitudinal foldable member or beam 23 is cut away along its underside so as to provide a clearance for trunnion 27 when the beam 23 is rocked about its pivot pins 25 to the erect position.

Extending from the inner face of the beam or transverse foldable member 22 is a rectilinear projection 29 which is adapted to be received in a complementary located opening 30 provided in the longitudinal beam 23.

40 When the projection 29 is seated within the opening 30, the members are held substantially erect and rigid in the vertical attitude shown.

To maintain the beam members 22 and 23 locked in the vertical attitude or erect operable position shown in FIG. 4, there is provided a latch member 31 pivotal about a pin 32 for movement in a vertical plane transverse to the longitudinal axis of the car 10. The latch member 31 includes a shank 34 of substantially rectangular section which is seatable in a notch 33 so that the upper side 37 lies substantially flush or coplanar with a planar horizontal support surface 35 formed on the beam 23. The latch member 31 is formed with a lip 36 which overlies the inner face of the longitudinal beam 23 and retains the latter in engagement with the inboard end of the transverse beam 22. In this manner there are formed two right-angularly disposed surfaces 35 and the surface 37 which engage the bottom of the container C as shown in particular in FIG. 6 and FIG. 7. Providing a stop or index surface against the side and end of the container C are upright surfaces 38 and 39 formed respectively on the brackets 23 and 22. The upright surfaces 38 and 39 are formed to engage the container C rear and side surfaces in close proximity to a corner thereof. Thus, as shown in FIG. 1 four sets of container support brackets 20 located at each of the corners of the container C are operative to restrain the latter against lengthwise and transverse movement of the car 10.

The vertical surfaces 38 abutting one end of the container C are operative to resist movement of the force applied at the other end to the container. Similarly the transverse forces applied along one side of the trailer are opposed or resisted by the vertical surfaces 39 contacting the container on the other side thereof.

As shown, each of the transverse and longitudinal foldable members are formed with inwardly inclined surfaces

40 and 41 which merge with the vertical surfaces 38 and 39 respectively. The inclined surfaces 40 and 41 serve to guide the container into position on the planar surfaces 37 and 35 provided by the bearing blocks 22 and 23.

For holding the container C on the channels 19 and the support brackets 20, there is slidably supported within a horizontal groove 44 formed in the bracket or foldable member 22, a latching bar 45. The latch bar 45 is formed with a more or less triangular nose portion 46 which is engageable within an opening 47 located in a fixed position on the container C. The diagonal 48 serves as a camming surface to positively lock the container to the beam members 22 and 23 planar surfaces.

Connected to the outer end of the latch 45 is an actuating handle 50 which is pivotal about a pivot pin 49 fixed to a projection 49a extending from the outboard upper end of the transverse beam 22. Connecting the handle 50 to the latch bar 45 is a pin 51 which is slideable in an elongate vertical slot 52 of the bar 45. Normally the handle 50 is biased to a closed position in which position the triangular nose 46 extends outwardly of the vertical stop surface 39 as shown in full lines in FIG. 4. The handle 50 is biased into this position by means of a leaf spring 53 which is fixed at one end by means of a strap 54 to the top of the beam 22 and of which the free end is engageable with the top horizontal surface 55 of the handle 50 to apply a resilient force tending to move the handle 50 counterclockwise. To retract the latch, the handle 50 is moved clockwise as viewed in FIGS. 4 and 6 against the force of the biasing spring 53 until the triangular nose 46 is retracted free of the side of the container C and outwardly of the opening 47.

The handle 50 may be retained in the open position shown in FIG. 6 by means of a strut 56 which is pivotally secured intermediate the ends of the handle 50 by means of a pin 57. Normally, the strut 56 lies within a slot provided in the handle and is movable about the pivot pin 57 to the position shown in phantom lines in FIG. 6 so that the free end thereof is engageable with a notch 58 formed on the outboard side of the bracket 22. It is to be noted when the handle 50 is thus propped it projects outwardly of the side sill 15 and serves as a visual indicator showing the latch 45 is in the open position. When the strut 57 is disengaged from the notch 58 the leaf spring 53 acting on top of the handle 50 is operative to urge the latter counterclockwise about the pivot pin 49 so that the latch member 45 assumes the locked position inwardly of the side sills 15.

In operation of the car 10, the four container support brackets 20 for supporting the container C may be in the collapsed or folded position shown in FIG. 5. To support a container a set of four of the brackets are erected to receive the container corners. First, the beam 22 of each of the brackets 20 is raised about the pivots 26 to the erect position shown in FIG. 3. Thereafter the beam 23 is rotated about the pivot pins 25 so that the opening 30 seats over the projection 29 on the transverse beam 22 and the latch 31 is turned to the locked position within the notch 33 with the lip or hook portion 36 engaging the inner face of the longitudinal beam 23. With each of the corner support brackets 20 in the operative position the container C is then placed into position for support thereon.

Generally, the container is lowered by way of a suitable crane lift into a position on the support brackets 20 and the lengthwise extending channels 19. As the container C approaches the support brackets 20, the bottom corners of the container strike the indexing surfaces 40 and 41 on the beam members 23 and 22 respectively so that the container is guided unto the planar surfaces 37 and 35 for support thereon. Note that the container C is thus operative to main the latch engaged within the notch 33 and thereby maintain the beams 22 and 23 in the erect position.

As the bottom corner edges along the sides and ends of the container C strike the respective indexing or in-

clined surfaces 40 and 41, the bottom container edges also engage the diagonal face 47 of the latch 45 so that the latter is urged outboard against the force of the spring 55 acting on the handle 50. When the container bottom engages the planar surfaces 37 and 35, latch 45 aligns with the opening 52 and the spring 53 acting on the top of the handle 50 is operative to urge the latch 45 and the nose 46 therein. In this manner the latching devices 45 on each of the corner brackets 20 are operative to lock the container C on the railway flatcar.

Removal of the container is achieved by retracting the handles 50 outboard of the side sills 15 so that the latch 45 is retracted out of the openings 47 and thereby permitting the container C to be elevated out of engagement with the corner brackets 20. During this period the struts 56 may be seated within the notch 58 to maintain the latch 45 clear of the container sides.

Referring now to FIGS. 8 and 9 there is shown one manner of recessing the plate brackets 22 and 23 of the bracket structure of FIGS. 4 through 7 into the floor structure. As discussed hereinbefore, it is desirable that the deck 16 be retained as free of obstructions as possible to permit the rapid transport of tractors and semi-trailers thereover. Heretofore, the corner brackets or mounting brackets were cumbersome so that it was virtually impossible to recess the decks to accommodate the same. However, with the present invention wherein the beams 22 and 23 of the support brackets 20 are relatively foldable to each other, the recessing within the deck 16 is made feasible.

As shown, this may be accomplished by the provision of ramp blocks 59a, 59b, and 59c. The ramp blocks 59a, 59b, and 59c are tapered so as to provide a gradual incline from level of the floor 16 to the maximum height at which the beams 22 and 23 project above the level of the floor 16. The block 59a is contoured to accommodate the bearing block or trunnion 24 and is arranged to be adjacent the bottom edge of the transverse beam 22. The incline block 59b is cut out along one edge to conform to the contour of the handle side or top side of the beam 22. The incline block 59c is formed to rise to a ridge 42 and thereafter again taper downwardly toward the floor 16. The incline block 59c may be also contoured to lie flush at either end with the longitudinal inboard edges of the blocks 59a and 59b and to accommodate the beam 23 therebetween.

Referring now to the container support bracket 21 shown in FIGS. 10 to 13, these container brackets 21 are utilized to concurrently support the two adjacent ends of the smaller size containers, while the container support brackets 20 are used at the remote ends of the containers. In this connection, it should be mentioned that when the small size containers, for example, the ten and five foot standard containers, are employed, the spacing on the car between the two is generally of lesser magnitude than that of the larger thirty or forty foot containers as shown in particular in FIG. 1. When the containers are positioned in closer proximity to each other, it is possible to utilize the arrangement of the container brackets 21. It is to be noted, that the container bracket 21 of the present invention when not in use may be folded to the inoperative position substantially flush with the floor 16 so as to lie beneath the larger size container supported solely on the corner bracket arrangement 20 as shown in FIG. 1.

For the purpose of description of the container brackets 21, those elements which are the identical to those employed in the embodiments of FIGS. 1 to 9 are identified the same. As shown the container bracket 21 comprises essentially a longitudinally extending beam 61 and a pair of laterally disposed and lengthwise spaced transverse beams 22 substantially identical to those employed in the embodiments of FIGS. 1 to 9.

The longitudinal beams 61 are turnably supported on the base or floor 16 by means of the pivot pins 24 carried by the pivot brackets or trunnions 25. The brackets or beams 61 are each formed with an upwardly extending

index projection 62 located substantially midway between the ends thereof and which is more or less triangular at its upper end so as to provide a pair of oppositely inclined guiding surfaces 63—63. The inclined surfaces 63—63 merge at the lower end with respective upstanding walls 64—64 against which the end walls of the containers C are adapted to abut. Extending from the vertical walls 62 are horizontal planar surfaces 65—65 providing support for the bottom of the containers C. The horizontal planar surfaces 65 are each provided with a notch 65a which is located so as to receive the shank 34 of the latch 31 therein, whereby the upper surface 37 of the latch 31 thereof lies substantially flush or o-planar with the horizontal surfaces 65—65. The lips 36 of each of the latches 31 pivotally supported on the transverse beam 22 as in the embodiment of FIGS. 1 to 7 lie outwardly of and engage the inboard surface of the beam member 61 so as to hold the latter erect. The rectangular projection 29 extending from the member 22 engages within the respective complementary openings 66 in the transverse beam 61. Thus the two transverse beam members 22 and the longitudinal beam member 61 mutually co-act to hold each other in the erect position similarly to the previously described embodiment. The transverse beam members 22 each include the container locking latch 45 which is normally urged into engagement with the opening 47 along the side of the container by way of the leaf spring 53 engaging the handle 50 to which the inner end of latch 45 is fixed.

To mount the shorter containers C on the right end of the railway car 10 shown, four of the corner support brackets 20 are erected, as are also the two dual corner support brackets 21 intermediate the corner support brackets 20. The corner support brackets 20 are erect as described in connection with the embodiment of FIGS. 1-7.

The dual corner support brackets 21 are erected by initially turning the transverse beams 22 to an upright position. Thereafter, the longitudinal beam 61 is turned or pivoted to its upright position whereupon the openings 66 on either side of the upstanding projection 62 receive the respective rectangular projections 29 on the inboard side of the transverse beams 22. The beam members 61 and 22—22 are held locked by engagement of the latch 31 within the notches 65a.

The shorter containers C are each lowered between respective sets of two corner support brackets 20 and two dual corner support brackets 21. During lowering the inclined surfaces 63 on the beams 61, the inclined surfaces 40 and 41 on the longitudinal beams 23 and the transverse beams 22 serve to guide the corners of the containers C into seating engagement within the respective support brackets 20 and 21 with the ends and side walls in engagement with upright surfaces 38, 39, and 64 and horizontal planar surfaces 35, 37 and 65. In this manner the smaller length containers C are indexed longitudinally and transversely of the car 10.

The containers C are each locked on the support brackets 20 and 21 by means of the latch bar 45 which engages within the standard opening 47 along the side of the container C as described in connection with FIGS. 1-7.

In the foregoing embodiments of container support brackets 20 and 21 it is to be noted that the side and end wall surfaces adjacent the corners of the containers are employed to index the latter longitudinally and transversely on the flat car. Under some circumstances the container C may be of the type which is provided with openings located along the bottom surface of the container adjacent each of the corners thereof. These openings are used for the purpose of either indexing or attaching the container to some suitable support structure. FIGURES 14 through 19 illustrate an embodiment of container mounting bracket 67 particularly adapted for use with containers of the type having indexing or openings U on the bottom adjacent the corners thereof.

Referring first to the mounting bracket structure 67 disclosed in FIGS. 14 through 17 and which are adapted to be employed with the larger length containers C similar to the corner brackets 20, the brackets 67 each comprise essentially a foldable member 68 extending longitudinally of the car and a folding member 69 extending transversely of the car.

The longitudinal beam 68 is pivotal about pivot pins 70—70 carried by pivot blocks 71—71 located adjacent the ends of the beam 68. As shown, the blocks 70 are of substantially U-shaped contour having a cut-out 72 accommodating the ends 73 of the pivot beam 68. The longitudinal beam 68 is also pivotal at its center portion about a pivot pin 74 carried by a pivot block 75 fixed to the floor of the railway car. The center portion of the beam 68 is formed with a cut-out 76 so as to straddle the pivot block 75.

As shown, the upper end of the longitudinal beam 68 is formed with a triangular portion 76 merging at the base with a substantially rectangular section 77 which is engageable with the outer circumference of the opening U on the underside of the container C. The rectangular section 77 is formed with vertical sides 78—78, from the bottom ends each of which there projects horizontal ledges 79—79 upon which the bottom of the trailer or container is adapted to rest as shown in FIGS. 15 through 17. It is to be observed that the rectangular section 77 and upwardly extending triangular portion 76 lie substantially along the diameter of the index opening U.

The transverse beam 69 is formed of substantially right triangular contour and includes at one corner thereof a downward projection 80 which is received between a cut-out 81 of a pivot block 82 to which it is pivotally secured by means of a pivot pin 83. At the right angular corner the transverse beam 69 is pivotally connected to the block by means of a pin 83a. In this manner the beam 69 is foldable from a position adjacent the floor to an erect position as shown respectively in FIG. 14 and FIG. 15. In the erect operative position a latch member 84, pivotally secured to the beam 69 by means of a pin 84a and extending through an opening 85 is inserted through an opening 86 in the rectangular section 77 of the beam 68 so that a lip 87 engages the outboard face of the former. In this position the latch 84 rests within a groove found in a horizontal surface or ledge 79a and the transverse beam 69 and the longitudinal beam 68 mutually support each other in an erect position.

The member 69 is formed at its upper end with a substantially right triangular section 88 having a slope complementary to the triangular portion 76 on the beam 68. The right triangular section 88 merges with a rectangular section 89 which is substantially one-half the length of the rectangular section 77 of the beam member 68. Thus, a vertical surface 90 on the rectangular section 89 and the vertical surfaces 78 on the rectangular section 77 of the beam 68 lie on a common circumference. The triangular portions 76 and 88 and the rectangular sections 77 and 89 form in the nature of an index cone 91 which is adapted to be received within the opening U in the container C to hold the latter fixed against lateral or longitudinal movement on the railway car 10. Moreover, when the container C is thus seated on the cone 91 the container bottom rests on the horizontal ledges 79—79, 79a and the upper surface of the latch 84.

For retaining the container C locked on the beams 68 and 69 there is provided a pivotal latch 92 which is pivotally secured by means of a pin 94 for movement along one side of the longitudinal beam 68 from an inoperative position as shown in phantom lines on FIG. 7 to an operative position in which a hook or lip 93 formed on the upper end of the latch is inserted within the opening 47 along the side of the container C. As shown, the latch 92 is formed with a flat surface 96 which in the locked operative position is substantially vertical. En-

gageable with the flat surface 96 is a locking block 97 which is pivotally mounted on one end by means of a pivot pin 98 to a pivot bracket 99 projecting upwardly from the diagonal of the transverse beam 69. The locking block 97 is movable in a plane transverse to the turning movement of the latch 92 and when the inner surface of the block overlies and engages the flat surface 96, the latch 92 is restrained against turning so that the lip 93 is engaged in the opening 47.

Referring now to FIGS. 18 and 19, there is shown a further form of intermediate container support bracket 100 for use with containers having bottom openings adjacent the corners thereof. The modified intermediate container support bracket 100 is similar to that shown in FIGS. 14-17 but is arranged to concurrently support the adjacent ends of two smaller length containers C. In the following description, those elements of the intermediate support brackets 100 which are identical to the elements of support brackets 67 will be designated by the like reference character.

As shown, the intermediate support bracket 67 includes a longitudinal beam 101 which is adapted to be folded between a position on the floor 16 and an erect position, and a pair of lengthwise spaced transverse beams 69. The transverse beams 69 are substantially identical to those disclosed in the embodiment of FIGS. 14-17 and are mounted for pivoting movement on pivot pins 83a and 83. The transverse beams 69 each includes at the apex thereof a right triangular section 88 from the lower diagonal corner of which there extends the vertical surface 90 of the rectangular section 89. Projecting from the vertical surface 90 is the horizontal surface 79a in which the latch 84 is seated within a groove so that the upper surface thereof lies substantially coplanar. The latch 84 is pivotally attached to the beam 69 by means of a pivot pin 84a.

The beam 101 includes a pair of lengthwise spaced upwardly extending triangular portions 76-76 and rectangular sections 77 which coat with each of the right triangular portions 88 and rectangular portions 89 and thereby to form two lengthwise spaced conical members 91 which are adapted to be received within the respective conical recesses V in the adjacent containers C-C, as shown. The longitudinal beam 101 is turnably supported by means of pivot pins 102-102 mounted in spaced trunnions 102a located adjacent the ends thereof and pivot pins 103-103 carried in ends of a block 104 which is disposed between depending trunnions 105-105 on the underside of the beam 101.

For retaining the adjacent ends of containers C-C on the container support or mounting brackets 100 there is provided a pair of pivotal latches 106-106 which are mounted on the inboard side of the longitudinal beam 101. As shown, the pivotal latches 106-106 are turnable in the plane of the inner wall of the beam 101 about pivots 107-107 so that the lips 108 are engageable within openings V adjacent to corners of the container C. In this manner the adjacent ends of the containers C-C are retained locked on the container mounting brackets 100.

To prevent the lips 108 from becoming disengaged there is provided a locking block 109 which is pivotally connected at one end by means of a pivot pin 110 to an upstanding flange 111. The locking block 109 is movable in a plane transvers to the plane of movement of the pivotal latches 106-106 from an upright position to a position between the pivotal latches. In this position the opposite side surfaces of the locking block engage the adjacent edges of the pivot latches 106-106 and prevent turning movement thereof about the pivots 107-107 so that the lips remain engaged within the openings 109.

To release the adjacent ends of the containers C from the support brackets 100 the locking block 109 is turned out of engagement between the latches 106-106 so that the latter are free to turn about the respective pivots 107

whereupon the lips 108-108 may be disengaged from the openings V.

It is of course understood that the remote ends of the containers C-C are supported or mounted on the brackets 67, the operation of which has been heretofore described.

What is claimed is:

1. A container mounting bracket for demountably mounting containers on a railway car having a floor, said container mounting bracket comprising a first flat beam member extending transversely of said car, means mounting said first flat beam member on the car floor for turning movement from a horizontal rest position on the car floor to an erect position substantially normal to the floor, a second flat beam member extending longitudinally of said car, means turnably mounting said second flat beam member on the car floor for turning movement between horizontal rest position on the car floor and an erect position substantially normal to the car floor, means on said first and second flat beam members being interengageable and coacting to provide mutual support for each other in the erect position thereof, abutment surface means on said first flat beam members adapted to engage a side wall of said container to resist horizontal load forces on said container applied laterally of said railway car, and abutment surface means on said second flat beam member adapted to engage an end wall of said container resisting horizontal forces applied on said container longitudinally of said car.
2. A container mounting bracket for a railway car having a floor and adapted to support the adjacent ends of two end-to-end containers thereon, said container mounting bracket comprising a first flat beam means extending transversely of said car, means mounting said first flat beam means on the car floor for turning movement from a horizontal rest position on the car floor to an erect position substantially normal to the floor, a second flat beam member extending longitudinally of said car, means turnably mounting said second flat beam member on the car floor for turning movement between a horizontal rest position on the car floor and an erect position substantially normal to the car floor, said first flat beam means and said second flat beam member including interengageable and coacting means to provide mutual support for said first beam means and said second beam member in the erect position thereof, abutment surface means on said first flat beam means to resist horizontal load forces applied on the said two containers laterally of said railway car, and lengthwise spaced abutment surface means on said second flat beam member resisting horizontal forces applied on said containers longitudinally of said railway car.
3. The invention as defined in claim 2 wherein said first flat beam means comprises lengthwise spaced flat beam members, said flat beam members each including vertical abutment surface means adapted to engage the respective sides of each of said end-to-end containers, and said lengthwise spaced abutment surface means on said second flat beam member are vertically disposed to engage the respective ends of said end-to-end containers.
4. A container mounting bracket for a railway car having a floor and adapted to support a container having a substantially circular index opening, said mounting bracket comprising a first flat beam member extending transversely of said car, means mounting said first flat beam member on the car floor for turning movement from a horizontal rest position on the car floor to an erect position substantially normal to the floor, a second flat beam member extending longitudinally of said car, means turnably mounting said second flat beam member on the car floor for turning movement between a horizontal rest position on the car floor and an erect position substantially normal to the car floor, said first and second flat beam members including means interengageable and coacting to provide mutual support for each other in the erect position thereof, a first upwardly extending surface means on said first flat beam member adapted to radially enter said index opening.

opening and having abutment means engageable within the index opening to resist horizontal load forces applied laterally of said railway car, and second upwardly extending surface means on said second flat beam member adapted to radially enter said index opening and arranged at a substantially right angle to said first upwardly extending surface means on said first flat beam member and having abutment means engageable within the index opening to resist horizontal forces applied longitudinally of said car.

5. The invention as defined in claim 4 wherein a said first and second upwardly extending surface means are formed to provide a substantially semi-conical indexing head when said first and second beam members are in the upright positions thereof.

6. A container mounting arrangement for supporting a plurality of containers in end-to-end relationship on a railway car comprising dual container mounting brackets adapted to accommodate and support the adjacent ends of two end-to-end disposed containers thereon along the corners thereof and container mounting brackets adapted to accommodate and support the remote ends of said two containers adjacent the corners thereof, said dual container mounting brackets each comprising a pair of lengthwise first flat beam members extending transversely of the car and having an abutment surface means adapted to engage the side walls of each of said two containers, a second flat beam member extending longitudinally of said car and having abutment surface means adapted to engage the end wall of said container, means mounting each of said first and second flat beam members on the car floor for turning movement between a horizontal rest position on the floor and an erect position substantially normal to the floor, and coacting means on said first and second flat beam mem-

bers to maintain said first and second beam members in said erect position whereby each of said container support brackets at the respective corners of said containers are operative to resist longitudinal and lateral movement of said two containers concurrently supported thereon, and said container support brackets supporting said remote end corners of said end-to-end containers comprise a first flat beam member and a second flat beam member arranged at substantially right angles to each other, means mounting each of said first and second flat beam members on the car floor for turning movement between a horizontal rest position on the car floor to an erect position substantially normal to the car floor, coacting and interengaging means on said first and second beam members to provide mutual support for said first and second beam members in the erect position thereof, said first and second flat beam members each having vertical abutment surface means engaging the end and side walls of the respective remote ends of said containers to resist longitudinal and radial movement of said containers.
